(57) **CLAIM**

The ornamental design for a packaging container as shown and described.

DESCRIPTION

FIG. 1 is a perspective view of a packaging container showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a front perspective view of the packaging container, in an opened configuration;

FIG. 7 is a front view of FIG. 6;

FIG. 8 is a rear view of FIG. 6;

FIG. 9 is a left side view of FIG. 6;

FIG. 10 is a right side view of FIG. 6;

FIG. 11 is a top plan view of FIG. 6; and,

FIG. 12 is a bottom plan view of FIG. 6.

The broken lines depict portions of the packaging container that form no part of the claimed design.

1 Claim, 12 Drawing Sheets
